[57] ABSTRACT

In cargo-handling apparatus having a spreader conformably fitting and attaching to a cargo container, the improvement characterized by having a carriage means supportingly engaging a transverse support member of the spreader such that the carriage means is reciprocally movable laterally of the spreader so as to be able to move at least one end of the spreader to skew it over such that its conforming corner attachments will mate with those on the cargo container. Also disclosed are specific preferred arrangements wherein the spreader is moved with respect to the carriage by a fluid powered cylinder, piston and shaft arrangement; and wherein movable carriages are employed at each end of the spreader for doubling the amount of skew attainable.

SPREADER SKEW ARRANGEMENT

BACKGROUND OF THE INVENTION

1. Field of the Invention

This invention relates to load-handling apparatus; and, more particularly, to cargo-handling apparatus in which a spreader conformably engages a cargo container for transporting the cargo container from one location to another.

2. Description of the Prior Art

A wide variety of load-handling apparatus has been devised. For example, large cargo containers have been developed to save the cost of individually and laboriously transporting numerous smaller items. These large cargo containers have been handled by spreaders, a structural frame that conformably engages and attaches to the cargo containers. The spreaders have support means such as a plurality of cable and sheave arrangements at each end for picking up the cargo containers.

Heretofore, however, it has been difficult for the operator of a large crane such as a dock crane to effect the desired alignment of his cable-suspended spreader with a cargo container many feet below him; such as, in the hold of a ship. Frequently, it necessitated the help of an additional workman to align the spreader, negating part of the savings of the load-handling apparatus.

Thus, it can be seen that the prior art cargo-handling apparatus, though much improved over use of individual laborers, has not been totally satisfactory in effecting automated handling.

BRIEF DESCRIPTION OF THE DRAWINGS

FIG. 1 is a partial isometric view of a typical load-handling crane such as a dock crane employing one embodiment of this invention.

FIG. 2 is a perspective view of a cargo spreader such as employed in FIG. 1, and employing an embodiment of this invention.

FIG. 3 is a perspective view of a cargo spreader employing another embodiment of this invention.

DESCRIPTION OF THE PREFERRED EMBODIMENTS

It is a primary object of this invention to provide apparatus enabling remotely aligning a spreader with the cargo container it is to pick up; the remote aligning being effected by the operator of the large equipment that will ultimately pick up the spreader, and without requiring an additional workman.

Referring to FIG. 1, a spreader 11 conformingly and supportingly engages cargo container 13 in suspension; and is, in turn, carried by main support beam 15 via cables 17 depending therefrom. Cables 17 engage a hoisting drum on platform 19 and suitable sheaves on the spreader 11. The main support beam 15 is reciprocally movable within a main support frame 21 of a vehicle 23. As illustrated, the vehicle 23 is a dock crane, although it may be any other large crane suitable for the area in which the cargo container 13 is to be moved, or transported. In any event, the vehicle 23 is supported by suitable bases 25. The bases 25 are mounted on a plurality of suitable wheels, or tracks, 27 for movement along a surface such as a dock. The vehicle 23 and the main support beam 15, as well as cables 17, move responsively to controls by the operator in the operator's console 29. The operator's console 29 may be many feet; for example, 70 feet or more; from the surface on which is emplaced the cargo container with which spreader 11 is to be conformingly aligned in order to supportingly engage it. The operator can move the vehicle 23 along its longitudinal axis forward or rearward, can move main support beam 15 along the lateral axis of the vehicle 23, and can move spreader 11 vertically; all with relative ease. The vehicle 23 is relatively difficult maneuverable for effecting fine corrections other than along its longitudinal axis. Consequently, in the event the cargo container has become slightly skewed, as by the pitching or rolling of a ship, the operator heretofore has had difficulty in skewing the spreader 11 to conformingly engage the cargo container 13. With this invention, however, the operator can

now effect lateral movement of one or both ends of the spreader 11 to effect the desired alignment with the cargo container.

Referring to FIG. 2, the spreader 11 has a plurality of transverse, spaced apart support members 33 and 35 rigidly affixed thereto. As illustrated, the support members 33 and 35 are disposed adjacent respective ends of the spreader 11. The respective support members 33 and 35 are supportingly suspended from respective suspension support means, which comprise cables 17 and respective sheaves 37 and 39. The elements described hereinbefore, including the respective suspension support means, form a means for raising and lowering the load. The means for raising and lowering the load ultimately lifts spreader 11 and its cargo container 13 by its support members 33 and 35, which must be structurally adequate for this purpose. Each transverse support member may comprise a unitary structural member or a plurality thereof.

As illustrated, sheaves 37 suspendingly and supportingly engage transverse support member 33 via its block 41 at a fixed location, as by a pin shaft 43.

At the other transverse support member 35, however, a carriage means such as carriage 45 suspendingly and supportingly engages the support member 35. The carriage 45 is reciprocally movable laterally of the spreader 11 and longitudinally along the support member 35 by way of rollers 47 engaging a recessed groove, or track, 49 in the transverse support member 35.

A drive means is connected with the spreader 11 and with the carriage 45 for reciprocally moving the carriage 45 along the lineal axis of the transverse support member 35; or, more importantly, for moving the end 51 of the spreader 11 with respect to carriage 45 to effect alignment of the spreader 11 with the cargo container 13 it is to pick up. Specifically, a shaft 53 is connected with carriage 45 and to a piston within cylinder 55. Respective fluid conduits 57 and 59 connect the ends of cylinder 55 with a four-way valve 61. The four-way valve 61 is connected at its high pressure side via conduit 63 with a pump 65, and at its low pressure side via conduit 67 with reservoir 69. Pump 65 is connected with reservoir 69 via conduit 71. Pump 65 is also drivingly connected with motor 73. The motor 73 and the four-way valve 61 are connected with the operator's console 29, FIG. 1, via suitable conductors 75 for control by the operator.

In operation, the operator in his elevated operator's console 29 effects movement of the vehicle such as dock crane 23 along the dock to position platform 19 above the point at which the cargo container 13 is to be picked up. The location may be above the hold of a ship. The spreader 11 is lowered to the point immediately above the container 13. In the event that the container and the spreader are not in alignment, the operator effects movement of the end 51 of spreader 11 in the desired direction through suitably supplying high pressure fluid through either fluid conduit 57 or 59 to effect a high pressure on one side of the piston in the cylinder 55. Thus, the shaft 53 responsively moves carriage 45 laterally along the transverse support member 35. Ordinarily, the amount which the end 51 has to be moved will be slight and will be readily effected even though there may be a reaction movement of the carriage 45. Ordinarily, the reaction movement of the carriage 45 will be slight. Once alignment is effected, the spreader 11 is lowered to conformingly and supportingly engage cargo container 13. The engagement is well known and need not be described in detail herein. Briefly, the respective corners 77 comprise skirts to guide the spreader 11 over the corners of the cargo container 13. Suitable latch members engage openings in the cargo container to effect the attachment of the spreader 11 to the cargo container 13. Thereafter, the operator lifts spreader 11 and the cargo container 13 until it clears the obstacles between it and its destination. He then positions the platform 19 and the cargo container 13 through suitable movement along main support beam 15, with or without movement of the main support beam 15 and the vehicle 23.

He then lowers the cargo container 13 onto its new resting location, disengages, and returns to pick up another container.

Another embodiment of this invention is illustrated in FIG. 3. Therein, both ends 51 and 79 have respective carriage means such as carriages 45 and 45a. Each carriage 45 and 45a has its individual drive means and its individual support means. Specifically, carriages 45 and 45a each have a respective cylinder, piston and shaft arrangement to move it laterally of the spreader 11 in response to suitable signals from the operator. Each of the respective cylinder, piston and shaft arrangements have their own respective four-way-valve, hydraulic pump, motor and hydraulic reservoir, with the respective conduit interconnections, as described hereinbefore.

The operation of the embodiment of FIG. 3 is essentially the same as described hereinbefore with respect to FIG. 2. The advantage of the embodiment of FIG. 3 is that the operator can move one end in one direction and the other end in the opposite direction to effect twice as much relative degrees of skewness to align the spreader 11 with the cargo container 13.

Once the idea of employing the reciprocally movable carriage for effecting the requisite skewness for alignment has been delineated, various drive means for effecting the relative lateral movement between the carriage 45 and the spreader 11 will come readily to mind. For example, a rack and pinion arrangement with a respective motor means turning the pinion may be employed with each carriage 45. Moreover, other means of maintaining the carriage supportingly engaging the transverse support members can be employed. For example, pads may slidably and supportingly engage the transverse support members instead of having the rollers 47 in their respective recessed grooves 49.

Thus, it can be seen that this invention enables an operator of a crane at his operator's console to remotely effect skewing of a spreader to align with a cargo container the spreader is to pick up; and thereby avoids the difficulties of the prior art. No exotic new materials are required since the invention can be made employing only those materials of construction ordinarily employed in this art. In addition, the reciprocally movable carriage 45 enables an operator to position a respective cable sheaves thereon effecting a more nearly balanced cargo container.

Although the invention has been described with a certain degree of particularity, it is understood that the present disclosure

sure is made only by way of example and that numerous changes in the details of construction and the combination and arrangement of parts may be resorted to without departing from the spirit and the scope of the invention.

What is claimed is:

1. In load-handling apparatus having means for raising and lowering the load, the improvement comprising:

- a. spreader means for conformably attaching to a cargo container; said spreader means having a plurality of transverse, spaced apart support members;
- b. carriage means supportingly engaging in suspension at least one of said support members, said carriage means being reciprocally movable laterally of said spreader means and longitudinally along said support member;
- c. positive drive means controllable by an operator for reciprocally moving said carriage means to selected positions laterally of said spreader means and along the at least one support member; and
- d. a sheave block having a shank portion fixed to said carriage, with cable means engaging said sheave block for raising and lowering the load;

whereby said spreader may be skewed by remote control to align with a cargo container by appropriate movement of said carriage means longitudinally along said at least one support member.

2. The load-handling apparatus of claim 1 wherein said carriage means reciprocally, suspendingly and supportingly engages a first transverse support member; and a second transverse support member has a sheave block having a shank portion suspendingly and supportingly engaging it at a fixed location with cable means engaging said sheave block for raising and lowering the load.

3. The load-handling apparatus of claim 1 wherein a respective carriage means reciprocally, suspendingly, and supportingly engages one of two longitudinally spaced said transverse support members, and each carriage means has its individual positive drive means and its individual sheave block suspension support means.

4. The load-handling apparatus of claim 1 wherein said positive drive means comprises a hydraulically powered cylinder, piston and shaft arrangement connected intermediate said carriage means and the frame of said spreader.
